(57) **CLAIM**

The ornamental design for a vehicle liftgate, as shown and described.

DESCRIPTION

FIG. 1 is a perspective view of a vehicle liftgate, according to an embodiment of the invention.

FIG. 2 is another perspective view thereof.

FIG. 3 is a front view thereof.

FIG. 4 is a rear view thereof.

FIG. 5 is a side view thereof.

FIG. 6 is a bottom view thereof; and,

FIG. 7 is a top view thereof.

Mirror images of side views that are not shown are within the scope of the claimed design though not illustrated.

Portions of the vehicle liftgate shown in broken lines form no part of the claimed design.

1 Claim, 7 Drawing Sheets
